PORTABLE POWER UNIT

Willie M. Shoffner, Dayton, Ohio

Application August 6, 1948, Serial No. 42,960.

4 Claims. (Cl. 74—16)

1

This invention relates to a portable power unit adapted for placement on a bench for driving various machine tools.

An object of the invention is to provide a portable power unit that can be placed on a bench for driving various machine tools, such as tools for forming sheet metal.

It is still another object of the invention to construct the portable power unit in such a manner that it will be solidly supported on a bench regardless of minor irregularities that develop in the tops of work-benches.

Further objects and advantages will become apparent from the drawings and the following description.

In the drawings:

Figure 1 is a perspective elevational view of the portable power unit of this invention;

Figure 2 is a perspective elevational view of the portable power unit taken from the side thereof opposite to that of Figure 1;

Figure 3 is a cross-sectional view taken along line 3—3 of Figure 2;

Figure 4 is a cross-sectional view of the construction of the motor mounting.

In this invention the portable power unit consists of a frame 10 that is composed of a pair of angle members 11 and 12 positioned substantially parallel to each other. The angle members 11 and 12, or side rails, are connected together at one end thereof by means of the cross-rail or angle member 13. The opposite ends of the side rails 11 and 12 are connected together by means of an angle member 14 that has a flange 15 thereon depending below the bottom surfaces 16 thereof. The angle members 11 and 12, respectively. A clamp pad 18 extends between the side rails 11 and 12 adjacent the front end thereof and adjacent the angle member 14. The side rails 11 and 12 are each provided with an arch from front to rear thereof, as can be seen by reference of the rail 12 to the dot-dash line 20. The rear connecting rail 13 is also provided with an arch between the ends thereof as can be seen by reference to the dot-dash line 21.

The arch provided in the side-rails 11 and 12 and in the rear rail 13 provides an arrangement whereby the frame 10 will be supported on a horizontal surface by the ends of the rails 11, 12 and 13. Thus, irregularities in the surface of a work-table or bench will not affect the stability of support of the power unit on a work-table.

At one end of the frame 10 there is provided a metal box 25 that has open sides 25a and 25a. The box is provided with a bottom wall 26 that is

2

suitably flanged so that the box can be bolted between the side-rails 11 and 12 by means of bolts 27.

An electric motor 28 is supported upon the bottom wall 26 of the box 25 and a speed-reducing unit 29 is supported on the upper wall 30 of the box 25.

The electric motor 28 is supported on the wall 26 by means of the bolts 31 and the resilient support bushings 32. The support bushings 32 are of a rubber-like material to provide for flexibility in the motor mount. A guide-pin 33 passes through an opening 34 in the base 35 for the motor 28 to prevent side sway of the motor.

15 The speed-reducing unit 29 is bolted to the box 25 in conventional manner.

The motor 28 and the speed-reducer 29 each have a multiple speed pulley on the respective drive shafts, such as pulleys 36 and 37 with a belt 38 extending therebetween.

20 The resilient mounting of the motor 28 provides for automatic belt tightening of the belt 38.

The output shaft of the speed-reducer 29 is connected to a telescoping power shaft 40 of a type disclosed in my copending application, Serial No. 781,961, filed October 24, 1947. This power shaft 40 consists generally of a universal joint 41 at one end thereof that connects to the output shaft of the speed reducer 29 and a universal joint 42 that is adapted to be connected to a machine for driving the same. A telescoping shaft 43 is provided between the universal joints 41 and 42 to take care of varying distances between machines that are to be driven by the portable power unit.

25 A support bracket 50 is secured between the side-rails 11 and 12 of the frame 10 and is provided with a socket 51 which receives the power shaft 40 to support the same when the device is not in use, and to prevent damage to the universal joint 42 in the event the power unit should accidentally be started while the power shaft is not connected to a machine.

The electric motor 28 is controlled by a foot-switch 56a for starting, stopping or reversing the action of the electric motor 28 which is of the type that can be operated in either direction of rotation.

30 A flexible electric cord 51 is provided for connecting the power unit with a suitable source of electric current.

35 From the foregoing description, it will be apparent that the power unit can be placed on a work-bench with the flange 15 against an edge of the bench. Thus, when the telescoping power

shaft 40, which is extended by means of a coil spring contained in it, is connected to a machine set on the bench or in front of the bench, the power unit will not slide rearwardly of the bench away from the machine to be driven. Also, a non-rocking support is provided for the power unit since the arched rail members 11, 12 and 13 will rise above the horizontal plane formed by the top of the bench to avoid engagement with minor irregularities on the surface of the work-bench.

A control switch 55 can be provided for controlling the flow of electric current to the foot-switch 50a.

While the apparatus disclosed and described herein constitutes a preferred form of the invention, yet it can be altered mechanically without departing from the spirit of the invention, and it is understood that those modifications that fall within the scope of the appended claims are intended to be included herein.

Having thus fully described my invention, what I claim as new and desire to secure by Letters Patent is:

1. A portable power unit comprising, a pair of frame members positioned side by side but in spaced relationship, said frame members having their lower surfaces formed in an arch relative to a horizontal plane, a frame member extending transversely between said pair of frame members at one end thereof, a second frame member extending transversely between said pair of frame members at the opposite end thereof and having a flange portion thereof depending below the arched surfaces of said pair of frame members, and a source of power carried by said pair of frame members at one end thereof opposite to said second transverse frame member.

2. A base for a portable power unit comprising, a pair of frame members positioned side by side but in spaced relationship, said frame members having their lower surfaces formed in an arch relative to a horizontal plane, a frame member extending transversely between said pair of frame members at one end thereof, said frame member having the lower surface thereof arched between opposite ends of the member, a second frame member extending transversely between said pair

5
10

of frame members at the opposite end thereof and having a flange portion thereof depending below the arched surfaces of said pair of frame members, said pair of frame members being adapted for supporting a power unit thereon at the end thereof opposite to said second transverse frame member.

3. In combination; a power unit and a base therefor especially adapted for bench mounting, said base comprising longitudinally and transversely extending frame members connected together, and at least some of said members being arched upwardly between their points of connection with the other members to provide spaced points of contact of said base with a bench top.

4. In a base for supporting a power unit; angle members forming side and end rails connected together adjacent their ends, the side rails and one end rail having their vertical flanges extending upwardly and being arched upwardly between their ends, and the other end rail having its vertical flange extending downwardly, said upwardly arched rails providing spaced points of contact of the base on a bench top, and the vertical flange on the said other end rail providing means to abut the side edge of a bench top, and means on the base adjacent the said one end member for supporting a power unit.

WILLIE M. SHOFFNER.
